United States Patent Office.

JOSEPH W. DOUGLAS, OF MIDDLETOWN, CONNECTICUT, ASSIGNOR TO
W. DOUGLAS AND B. DOUGLAS, OF SAME PLACE.

Letters Patent No. 74,321, dated February 11, 1868.

IMPROVEMENT IN PUMPS.

The Schedule referred to in these Letters Patent and making part of the same.

TO ALL WHOM IT MAY CONCERN:

Be it known that I, J. W. DOUGLAS, of Middletown, in the county of Middlesex, and State of Connecticut, have invented a new and useful Improvement in Pumps; and I do hereby declare that the following is a full and exact description thereof, which will enable others skilled in the art to make and use the same, reference being had to the accompanying drawing, forming part of this specification:

This invention relates to a new and useful improvement in pumps for domestic or household use, such as are commonly termed "yard-pumps;" and it consists in the combination and arrangement of parts, as will be hereinafter described. The accompanying drawing represents a vertical central section of my invention.

A represents the upper portion of the barrel or cylinder of a pump, B the spout or nozzle, and C the air-chamber on the top of the barrel or cylinder A. On the top of the air-chamber C, the stand D, in which the hand-brake or lever E is fitted, is placed, and allowed to turn freely, the stand being fitted on a thimble, F, secured to the top of the air-chamber, said thimble having a groove made circumferentially in its exterior surface to receive a set-screw, a, which passes through the lower end of the stand, as shown in the drawing. In the upper end of the thimble, a tubular screw, b, is fitted, through which the piston-rod G passes, said screw and the interior of the thimble F forming a stuffing-box. The stand D, it will be seen, may be turned on the air-chamber, and secured in any desired position relatively with the nozzle or spout B. In the upper part of the air-chamber there is a hole made, and tapped to receive a screw, H, which is provided with a shoulder, c, to fit, when the screw is screwed fully up, against a plane surface on the exterior of the air-chamber, around the screw-hole, and this plane surface has a number of holes, d, drilled through it, which holes, when the screw H is screwed outward, so that the shoulder c will not be in contact with the plane surface on the exterior of the air-chamber, will form a communication between the interior of the air-chamber and the external air. This screw, therefore, performs the function of a valve, and when a force-pump is not required, the screw H is unscrewed, to admit air to the air-chamber, and the pump will then operate like an ordinary lift-pump.

Having thus described my invention, I claim as new, and desire to secure by Letters Patent—

The combination of the pump A, air-chamber C, screw-pin H, thimble F, revolving stand D, and tubular screw b, all arranged as described, for purpose specified.

JOS. W. DOUGLAS.
